UNITED STATES PATENT OFFICE.

HARRY R. GEER, OF JOHNSTOWN, PENNSYLVANIA.

PACKING-RING.

1,088,143.

Specification of Letters Patent. Patented Feb. 24, 1914.

Application filed November 8, 1912. Serial No. 730,185.

To all whom it may concern:

Be it known that I, HARRY R. GEER, a citizen of the United States, residing in the city of Johnstown, in the county of Cambria and State of Pennsylvania, have invented 5 certain new and useful Improvements in Packing-Rings; and I do hereby declare the following to be a full, clear, and exact description of the invention, such as will enable others skilled in the art to which it 10 pertains to make and use the same.

My invention relates to packing-rings and more especially to metallic spring packing-rings for pistons of fluid pressure engines, 15 pumps and the like.

One of the objects of my invention is to provide a combination spring packing-ring for this purpose which is simple in construction, cheap to manufacture, which will maintain at all times a tight, but resilient fit between the piston and the wall of the cylinder without giving undue or frictional resistance against the wall, and adapted to automatically adjust itself as the contact 20 surfaces become worn.

I have found that the customary simple cast iron spring packing-rings in engine pistons are frequently broken into pieces, particularly in condensing engines, in which the 25 difference in the alternating pressures on opposite sides of the piston is marked. I have discovered that these customary simple cast iron spring packing-rings are often broken in use by slapping against the cylinder walls, or 30 against the grooves in the piston head, the slapping being caused by the sudden reversal of fluid pressures from one side of the piston to the other, and under certain conditions by the reversing movement of the 35 piston at the ends of its stroke. I consider, however, that most of the breakage of the 40 customary single cast iron piston rings, and the consequent trouble, such as cutting themselves and the cylinder walls, leakage, etc., 45 is due to the slapping action caused by the sudden reversal of pressure at the ends of the stroke of the piston, and to excessive pressures caused thereby or otherwise. During 50 the operation of a fluid pressure engine, especially of the condensing type, a vacuum or partial vacuum exists on one side of the piston at or about the time the initial or compressive pressures are highest on the other side of the piston, and this condition 55 is reversed as the movement of the piston

varies during its cycle of motion. This, therefore, causes pressure from the outside on the piston rings which contracts them, and then a pressure from the inside which expands them violently with the destructive 60 action above noted.

Another object of my invention is to prevent the slapping referred to, by providing inside of the wearing or packing-ring, one or more cut spring rings preferably so arranged 65 that the joints thereof are in staggered relation with that of the meeting ends of the packing-ring, while lugs or other suitable means are provided to maintain the rings in their relative circumferential positions. 70 The outer or packing-ring cannot contract without similarly contracting or reducing the diameter and circumference of each inner spring ring, and each ring must, during the time of its contraction, slide on 75 each of the adjoining rings at all points. This frictional resistance, on account of the clamping action, is greater during the contracting movement than during the expanding movement, but by reason of my construction it is sufficient at all times to preclude any violent slapping of the rings against each other, or the outer one against the cylinder wall.

A further object of my invention resides 80 in the manner of arranging an inner spring ring and an outer packing-ring, whereby their outer and inner surfaces are substantially concentric with the piston and cylinder; while their contact surfaces are eccentric, whereby a properly graduated spring 85 action is effected. I prefer to make the outer packing-ring of cast iron and the inner ring or rings of tempered spring steel, although other suitable materials may be 90 used, if desired.

Having thus given this general description of my invention, I will now, in order to make same more clear, refer to the accompanying sheet of drawings forming part 100 of this specification and in which similar characters refer to corresponding parts.

Figure 1 is a diametral transverse section of a piston of the umbrella type with a portion of the piston-rod in elevation connected thereto, showing my improved metallic spring packing-ring in cross section, mounted within the retaining groove which extends around the periphery of the piston. 105 Fig. 2 is a transverse section on an enlarged 110

scale of the spring ring and packing-ring taken on the line A—A of Fig. 4 through the overlapping meeting ends of the packing-ring and the thickest portion of the 5 spring ring. Fig. 3 is a transverse section on an enlarged scale of the spring ring and packing-ring taken on the line B—B of Fig. 4 showing the channel and rib connection between the split spring and packing 10 ring. Fig. 4 is a side elevation showing the general form of my improved packing-ring, the spring ring and the packing-ring each being of varying thickness, the thinnest portions of which are at their ends, while the 15 ends of the spring are diametrically opposite those of the packing-ring. The construction illustrated in Fig. 4 corresponds to that further illustrated in Figs. 1, 2 and 20 3 before mentioned. Fig. 5 is a side elevation illustrating another form of my invention in which a plurality of spring rings are used, each of which is of substantially the same thickness throughout its length, mounted concentrically in layers within the 25 outside packing-ring, which, as illustrated in this case, is also of uniform thickness throughout its length. Fig. 6 is an edge view of a portion of the packing-ring showing the overlapping scarfed meeting 30 ends of the packing-ring with parts thereof broken away to more clearly illustrate the construction for holding the spring ring and the packing-ring in the desired relative positions. Fig. 7 is a detail fragmentary side 35 elevation on an enlarged scale, of the spring rings and packing-ring, illustrated in Fig. 5 showing the stop pin for holding the plurality of spring rings in the desired position circumferentially within the packing- 40 ring. Fig. 8 is a transverse section on an enlarged scale taken on the line C—C of Fig. 5.

Referring now to Figs. 1, 2, 3, 4 and 6 and the various characters of reference 45 thereon:—1 designates a piston to which is attached centrally in any approved manner, the piston-rod 2. An annular groove 3 is formed around the periphery of the piston in which is mounted the packing-ring 4. Within this packing-ring is an inner spring member 5. Between the bottom of the 50 groove 3 and the adjoining surface of the inner spring-ring 5 a narrow space 6 is provided to allow limited clearance and movement of the rings. The outer or packing-ring 4 is preferably composed of comparatively soft, smooth wearing metal, such as 55 cast iron of proper quality, although any other suitable material may be used, if desired. The ends 7 preferably overlap as shown, being cut longitudinally of the packing-ring 4 as at 8 and transversely as at 9 to form a scarfed joint, although a square, 60 tapered, or other form of juncture may be

used. The spring ring and the packing-ring 65 are eccentrically mounted together and the spring ring is provided with a channel in its outer periphery as at 10 which extends nearly around its entire circumference, into 70 which projects the rib 11 formed on the inside of the packing-ring, as shown. The spring ring 5 and the packing-ring 4 are of tapered construction, each being preferably thinnest at its ends and gradually increasing in thickness to the opposite sides 75 thereof as shown, and the ends of the packing-ring are preferably opposite, or in staggered relation with, the ends of the spring ring, to provide proper joint and coöperation of these parts. The thicker central portion of the spring ring is not channeled, but is made solid of rectangular section, thereby forming abutments 12 at the ends of the channel which prevent, by contact with the 80 ends of the rib 11, relative circumferential 85 movement to any great extent, whereby the rings are maintained in proper positions with respect to each other.

In Figs. 5, 7 and 8 I have illustrated a slightly different form of a spring-controlled 90 packing-ring, but embracing substantially the same principles. In this form a plurality of split circular springs 13 are used, and in these figures three springs are shown, although this number may be varied, as desired. Each of these springs 13 is of substantially uniform thickness, and is mounted within the packing-ring 14 which is also of uniform thickness throughout, but preferably thicker than the spring rings. These 95 rings, however, may be of tapering thickness, if desired. This packing-ring has jointed ends 7 similar to the one previously described. The intermediate spring ring and the jointed ends 7 of the packing-ring 100 member are shown to be located on the same side of the piston, while the outer and inner spring rings have their ends on the opposite side thereof, as indicated. A pin 15 has its intermediate portion secured in a hole provided therefor in the central spring ring and the ends of said pin extend on either side thereof and project between the ends of the inner and outer spring members. One end of the said pin 15 enters a socket or depression 110 16 on the inside of the friction packing-ring member, thus preventing the different parts from changing their relative circumferential positions within limits.

It will be understood that the normal 120 tendency of the spring rings in either design is to expand or increase the diameter and circumference of the packing-ring member when in use, so as at all times to form a tight joint between the piston and the inner 125 wall of the cylinder, and although I have shown and described a piston with only one packing-ring, more can be used, if desired.

It has been customary, in some cases, to form the outer circumferential grooves in piston heads which receive the packing-rings, by making them of somewhat greater width than the packing-ring, or otherwise providing them with small communicating grooves or openings whereby steam or fluid under pressure can have ready access to the space between the bottom of the grooves in the piston and the inner surfaces of the packing-rings, and thereby act by pressure in setting out the packing-rings against the cylinder wall. I, however, prefer to make the annular groove 3 in the piston only very slightly wider than the rings which fit within them, in order to prevent excessive fluid pressures between the ring and the piston, as I do not rely upon this altogether for the action of my device.

In my design it is proposed to resist slapping of the packing-ring more by frictional resistance than by spring pressure. Fig. 5 illustrates a case where several split rings, with their ends oppositely disposed to each other, are employed. Due to this construction in which a number of springs are used, each of which has an outwardly tending pressure, as above described, the spring rings will readily expand the friction packing-ring member into any cylinder within their spring range, but will more strongly resist any contracting force tending to diminish their diameters and circumference to an extent or degree approximately in proportion with the number of spring rings or friction faces. This is caused by a cumulative clamping and frictional action between the adjoining surfaces of the springs which will more strongly resist any effort from the outside to contract or reduce the diameter of said rings, and this is a particular feature of my invention.

While I have shown and described my invention in considerable detail, I do not wish to be limited to the exact details of construction specified, but may apply the same to other purposes than those stated herein, and I may use such substitutions, equivalents or alterations thereof, as fall within the scope of my invention, and set forth in the claims.

What I claim as new and desire to secure by Letters Patent is:—

1. A packing-ring provided with thicker and thinner portions, comprising an outer ring with sidewise overlapping jointed ends tapering thence in both directions to the opposite thicker portion thereof, an inner tapered spring ring mounted within said outer ring, the thicker and intermediate portion of said inner ring being adjacent to the thinner end portions of the outer ring, and means for holding said rings in relative position.

2. A packing-ring provided with thicker and thinner portions, comprising an outer ring provided with a lapped scarf joint and tapering thence in both circumferential directions to an opposite thicker portion thereof, a tapered spring ring mounted within said packing-ring adapted to contact with the inner surface thereof, the thicker portion of which is adjacent to the joint in the outer ring and its thinner ends opposite thereto, a tongue formed on the inner surface of the outer ring, a small portion of said ring adjacent to the joint being unprovided with a tongue, a corresponding groove formed on the outer surface of the inner spring ring, except at the thicker portion thereof adjoining the joint in the outer ring aforesaid, forming an abutment on said inner ring adapted to contact with the ends of the tongue aforesaid, whereby said rings are maintained in relative position.

3. A packing-ring provided with thicker and thinner portions, comprising an outer ring the ends of which are scarfed and lapped, said ring tapering in both circumferential directions from the scarf jointed ends thereof to its thicker portion opposite said ends, an inner tapered spring ring mounted within and adapted to contact with said outer ring, said inner ring being arranged with its thicker portion adjacent to the thinner and jointed ends of said outer ring, the thinner open ends of said spring ring being adjacent to the thicker portion of said outer ring, and means for holding said rings in relative position.

4. A packing-ring comprising an outer ring provided with jointed ends, a plurality of elastically expansive spring rings mounted therein, the adjoining ends of which are in staggered relation with each other and the joint in the outer ring, whereby the spring rings will tend to expand the outer ring, but will more strongly resist a contracting force due to the frictional or clamping effect between the various contact surfaces.

5. A packing-ring comprising an outer ring of uniform rectangular section provided with jointed ends, a plurality of elastically expansive spring rings, each of rectangular cross section mounted therein, the adjoining ends of said spring rings being in staggered relation with each other and the joint in the outer ring, a recess formed in the inner surface of the said outer ring, a pin mounted in the intermediate portion of one of said spring rings, projecting within the said recess and between the opposing ends of the other spring rings, whereby said rings are maintained in relative position.

6. A piston provided with a circumferential groove of rectangular cross section, a packing-ring provided with thicker and

thinner portions, mounted therein, comprising an outer ring with jointed ends, an inner spring ring mounted within the outer ring aforesaid, the ends of said inner ring being in staggered relation with the joint of the outer ring, and means for holding said rings in proper relative position, whereby the spring ring will tend to expand the outer ring, but will more strongly resist a con-

tracting force, due to the frictional or 10 clamping effect between the contact surfaces.

In testimony whereof I hereto affix my signature in the presence of two witnesses.

HARRY R. GEER.
